UNITED STATES PATENT OFFICE.

GEORGE C. D. MILLER, OF NEW YORK, N. Y., ASSIGNOR TO CARY MANUFACTURING COMPANY, OF NEW YORK, N. Y., A CORPORATION OF NEW YORK.

BALE-TIE.

1,187,004.

Specification of Letters Patent. Patented June 13, 1916.

Application filed December 26, 1912. Serial No. 738,511.

To all whom it may concern:

Be it known that I, GEORGE C. D. MILLER, a citizen of the United States, residing in the city of New York, borough of Brooklyn, county of Kings, and State of New York, have invented a certain new and useful Bale-Tie, of which the following is a specification.

This invention is a new and useful bale tie, and is an improvement on a bale tie forming the subject matter of Patent No. 903,128, issued Nov. 3, 1908, to the assignee herein. Speaking generally, the said patent discloses a bale tie, the buckle of which consists of two members having wedging engagement, whereby the tie is securely gripped by said members. In one form of the invention shown in said patent, one of the said members is provided with a wedge-shaped socket for receiving the other member, said socket being formed by turned up lugs or jaws, the base lines of which are at right angles to the band tie.

The present invention relates more particularly to the structure and location of the said lugs and to the shape of the engaging member.

In the construction of the patented device referred to, notwithstanding its superiority over those of the prior art, the construction of the buckle is such that one member exerts a direct thrust on the other against the bend of the lugs, thereby subjecting them to such strain as to cause them to bend and release the tie when over-loaded. In other words, the bend of the lugs is at right angles to the longitudinal pull of the band, so that all the strain is so exerted as to tend to bend the lugs. In the improved construction, however, the thrust of one member of the buckle against the lugs of the other member is not direct, but at an angle thereto. That is to say, the base of each lug is at an acute angle to the longitudinal pull of the band. Accordingly, the lugs of the improved construction have very considerably less tendency to bend. A pronounced additional advantage, from the commercial standpoint, of the new bale tie over the old one, consists in the fact that it can be stamped out with less waste of metal, thereby rendering it much cheaper to manufacture.

In the accompanying drawings, I have

illustrated two practical embodiments of the invention, but the constructions shown therein are to be understood as illustrative, only, and not as defining the limits of the invention.

Figure 1 is a perspective view showing the elements of the buckle in coöperative relation to securely unite the ends of the tie band. Fig. 2 is a central section, taken longitudinally therethrough. Fig. 3 is a detail plan view of the base or main member of the buckle. Fig. 4 is a front edge view of the same. Fig. 5 is a plan view of the wedging member. Fig. 6 is a view showing the manner in which the blanks, from which the base members are formed, may be economically stamped from a sheet or strip of material. Fig. 7 is a plan view of a buckle of slightly modified form, the two clamping members being shown attached. Fig. 8 is a like view showing said clamping members in substantially normally clamped relation. Fig. 9 is a longitudinal section thereof, taken on line 9—9 of Fig. 8. Fig. 10 is a detail plan view of one of the complementary clamping members. Fig. 11 is a front edge view thereof. Figs. 12 and 13 are a plan and a section, respectively, of another construction of a member.

Referring more particularly to Figs. 1 to 6 inclusive, the buckle or tie is composed of a base or main member A, and a wedging or locking member B. These members are preferably stamped from sheet metal, preferably strip steel, and their structural shapes are conducive of the highest degree of efficiency. The base or main member A, is provided with an elongated slot a', through which one end of the tie band C, is passed. Said base member is semi-octagonal in shape, and is provided with a pair of upturned, spaced lugs a, one on either side of the longitudinal medial line a², of said member.

The lugs a, are bent up from the forward edge of the base member in such a manner that their bases a³, converge inwardly toward the center line of the direct pull exerted by the tie band C, as appears more particularly in Fig. 3, of the drawings.

The locking member B, is likewise, provided with a slot b', through which the other end of the tie band may be passed and secured to said member. This member has

its forward edges b , inclined at substantially the same angle and direction as the bases a^3 of the lugs a .

It will be obvious from the description given, that the opposite ends of the tie band are attached, one to each of the members, and said members are then brought into registering relation, as shown in Figs. 1 and 2. When thus positioned, and tension is exerted on the tie band, the inclined forward edges of the locking member, will coöperate with the upturned lugs on the base member, to set up a double wedging action. That is to say, the tension on the tie band will cause the locking member to be wedged tightly under each of the lugs, and, at the same time, the inclined forward edges of said member are being wedged between said spaced lugs. This double wedging action is of great importance since it imparts to a tie of the same weight of material, greater strength than that possessed by the old style tie. This is true from a theoretical as well as from a practical standpoint. In the old form, the pounds pull on the wedging member is exerted directly against the upstanding lugs. In others words, the lines of force are at right angles to the bases of said lugs, thereby tending to unbend them, and thus loosen the tie.

In the present invention, the pounds pull on the wedging member is divided into two distinct lines of force on each lug. These lines of force are, first, the wedging action, which is at right angles to the base of the lugs, and second, the sliding action which operates parallel with the bases of the lugs. The resultant force, or the direction in which the strain is really put on the lugs, is not at right angles to the lugs, as in the old form, but obliquely thereof, which is manifestly a pronounced advantage in favor of the new form. The increased strength thereby secured in the new tie permits its successful use in fields wherein ties of great strength are required, such as baling cotton.

Besides the novel structural features and functions hereinbefore set forth, the present invention is a marked improvement over the prior construction from a commercial standpoint. The contour of the base members of the buckle, is such that they can be stamped from a piece or strip of sheet metal with substantially no waste of material, as will readily be seen from an inspection of Fig. 6, of the drawings.

In assembling the tie, one end thereof is passed over the top of the member A, through the slot a' , and then bent upon itself around the reentrant part and passed backwardly over the top of the member. The other end of the tie band is passed under the wedging member B, over the back edge thereof, through the slot b' and thence backwardly upon the entering portion of the

bale tie. A band of the right length for the purpose intended having been provided, it is slipped around the bale, while the latter is under pressure in the baling press, and the member B, is placed in proper position relative to the member A, so that the forward edge of the said wedging member will engage the under or inner surfaces of the flanges a , on the base member. The pressure upon the bale is then relieved, whereupon the natural expansion of the bale produces a tension on the bale tie. The effect of this tension is to cause member B, to exert a double wedging action on base member A. It will be obvious that the greater the tension put upon the bale tie, the greater will be the wedging action and, as a result, the tie band is held very firmly and securely in place.

While the bale tie hereinbefore described is one of more than ample strength for all ordinary uses, yet, where still greater strength is required, I prefer to use the modified form of buckle, illustrated in Figs. 7 to 11, inclusive. This latter construction embodies the same basic principles as the former, the main difference being that, in the latter construction, both members of the buckle are provided with coöperating lugs, whereby a buckle of greatly increased strength results. This increased strength is largely due to the fact that the two additional lugs double the clamping or wedging surface of the buckle. In said Figs. 7 to 11, inclusive, both of the members D, D' of the buckle are identical in all respects, each having an elongated slot d , d' , through each one of which one end of the bale tie C may be passed. Each of the members is substantially semi-octagonal in shape, and is provided with a pair of upturned, spaced lugs e , e' . The lugs e , e' , are bent up, two from the forward edge of each member in such manner that their bases d^3 converge inwardly toward the longitudinal medial line 110 of the buckle.

It will be noted that the blank from which the form of clamping member shown in Figs. 7 to 11, is constructed, embodies the same salient features as the blank from which the construction illustrated in Figs. 1 to 6 is formed, the only difference being that, in the former, the forward edges of either of the buckle members, after the lugs are bent up, are in the same angular relation to the longitudinal medial line of its respective member as the oblique rear edges of said member. It will, therefore, be obvious that the blanks from which the modified form is constructed may likewise be struck up in a manner similar to that shown in Fig. 6.

It will be manifest from the description given, that the opposite ends of the tie band are attached one to each of the members D, D', and said members are then brought 130

into registering relation, as shown in Figs. 8, 9. When thus positioned, and tension is exerted on the tie band, the inclined edges d^2 of the member D, will coöperate with the 5 upturned lugs e' on the member D', and the inclined edges d^4 of the member D', will coöperate with the upturned lugs e , on the member D, to set up a double wedging action at each edge of the buckle. With this 10 construction and arrangement of parts, it will be obvious that, as the tension upon the tie band is increased, the wedging or clamping action between the buckle members will be correspondingly greater, whereby said tie 15 band is securely gripped against slipping.

In Figs. 12 and 13 there is shown another construction of member wherein an offset is provided to the end that abrupt bending of the tie is obviated. As shown, member E is 20 essentially the same as the parts heretofore described, *i. e.* it embodies a body portion, a slot therein, and over turned lugs. The improvement shown in Figs. 12 and 13 consists in offsetting one portion of the body at one 25 side of the slot, said offset producing a bar e joined by bends e' to the body, whereby the bar is in a different plane from the body. The tie C' is thrust straight through the slot and folded over the body, a part of the tie 30 resting within the offset and against one face of the bar. Of course, two members provided with offsets are employed in the complete buckle, and these members are assembled to secure the wedging action and 35 the clamping or binding of the two folded end portions of the tie.

Other slight modifications might be made, from time to time, to adapt the present invention to specific uses, and, accordingly, 40 applicant does not wish to restrict himself any more than the state of the art may require.

Having thus fully described the invention, what I claim as new, and desire to secure by 45 Letters Patent is:—

1. In a bale tie, a base member provided with two lugs inclined upwardly and inwardly toward each other and spaced apart on the forward edge of said base member, 50 combined with a locking member coöperating with said base member for securing the ends of a tie band together, said base member and said locking member provided with means for the attachment of a tie and said members adapted to receive the ends of the bale band between them and to be rocked toward each other by the pull of the bale band whereby the respective end portions of the tie are brought into frictional contact by the 55 strain of the tie upon said members.

2. In a bale tie, a base member provided with upturned spaced lugs positioned at the forward transverse edge of said member,

the bases of said lugs extending inwardly 65 at an angle to the longitudinal medial line, combined with a locking member, the forward edges of which are inclined correspondingly to the bases of said lugs, said base member and said locking member provided with means for the attachment of a tie and said members being adapted to receive the ends of the bale band between them and to be rocked toward each other by the pull of the bale band whereby the respective 70 end portions of the tie are brought into frictional contact by the strain of the tie upon the members.

3. In a bale tie, the combination of a base member adapted to receive one end of a tie band and provided at either side of the forward transverse edge of said member with a lug, and a second member adapted to receive the other end of said tie band and having portions of its forward edge converging 80 toward the medial line of said member, whereby the lugs of the base member and the forward edges of the second member coöperate to engage one another for interlocking relation.

4. In a bale tie, a member comprising a 90 body portion having a slot therein, and a pair of upwardly extending lugs integral with said body portion, the bases of said lugs being inclined toward a point outside of the body portion and in the medial line 95 thereof, combined with a second member positioned for locking engagement with said first member.

5. In a bale tie, the combination of a pair 100 of complementary members, each adapted to receive one end of a tie band and each embodying a substantially flat body portion, having an inclined lug at either side of the band engaging section thereof, each of said lugs converging inwardly toward the longitudinal medial line of its respective member.

6. In a bale tie, the combination of a pair 110 of complementary tension members, each embodying a slotted body portion adapted to be engaged by a free end of a tie band, and said body portion being provided with a pair of upturned inwardly inclined spaced lugs at the forward edge thereof, said complementary members coöperating with each other, the lugs at the forward end of either 115 member engaging the rear edge of the other member for securing the ends of said tie bands together.

In testimony whereof I have signed my name to this specification in the presence of 120 two subscribing witnesses.

GEORGE C. D. MILLER.
